UNITED STATES PATENT OFFICE

2,128,895

UNIT CONNECTER

William J. Buehring, Chicago, Ill., assignor to The
Reliable Electric Company, a corporation of
Illinois

Application April 24, 1935, Serial No. 18,028

4 Claims. (Cl. 173—263)

This invention relates to means for connecting wires, and more particularly to a unit connector. One feature of this invention is that it enables a wire to be connected to a line wire by a simple mechanical connector clamping them together; another feature of this invention is that it provides means for easily and simply getting a line wire into the connector; still another feature of this invention is that it is adapted to withstand high strains imposed by the clamping means; Other features and advantages of this invention will be apparent from the following specification and drawing, in which—

Figure 1 is a horizontal elevation of a connector; Fig. 2 is a side elevation of the same connector; Fig. 3 is a top plan view of the connector; Fig. 4 is a sectional view along the line 4—4 of Fig. 1; Fig. 5 is a sectional view showing the wire entering the connector; Fig. 6 is a side elevation of a modified form; and Fig. 7 is a transverse sectional view of the connector shown in Fig. 6.

The advantages of a mechanical connector for connecting a tap wire to a line wire, for example, have long been recognized. Many forms of connectors have been developed, all of them providing some means for clamping two wires in contact with each other. The majority of these connectors are not self-contained, or unit connectors, but comprise two parts which must be separated in order to place them in operative position with relation to the line wire. Such a connector is inconvenient and impractical for use in actual field work, since in the majority of cases the connection must be made by a lineman working at a disadvantage. Such a connector, comprising two separate parts, for example, cannot be easily connected to the line by a lineman working at the top of the pole and having only one hand free.

Even if the lineman is able to get the two parts of such a connector into proper operative relation with the line with the use of only one hand, he frequently drops one part or the other in endeavoring to connect them, as by threading them together. This results in a great waste of time in climbing up and down the pole, and in frequent lost connectors.

In order to overcome the disadvantages of these separable connectors, several forms of unit connectors have been developed for line work. All of the forms now in use, however, have proved to have serious defects. In one form, for example, the two parts have been slidably splined together in order to enable sufficient separation to admit the line wire. This form generally jams when it is tightened, and is of little use for any subse-

quent work. Another form, using a J-hook, has to limit the clamping pressure, and thus the tightness of contact between the wires, in order to prevent breaking of the J-hook, or else the hook has to be made extremely heavy.

This invention provides a unit connector which is simple, easy for a lineman to use, and structurally able to withstand high clamping strain. This connector consists of a substantially U-shaped yoke member having its ends closed by a yielding bridging member and provided with threaded clamping means. The entire connector is a unit, and no skilful manipulation of any kind is required to place it in operative position. A slight manual pressure enables the line wire to enter the yoke member past the yielding bridging member, whereupon the unit will then hang from the wire. The tap wire may then be inserted through the side and the clamping means tightened to hold the two wires in the desired contact.

In the particular embodiment of this invention illustrated herewith, the reference numeral 10 indicates a line wire which may be insulated, as indicated by 11. The connector has its main portion formed by the yoke member 12, which member is substantially U-shaped, as may be readily seen in Fig. 2. The upper ends 13 and 14 of the yoke member 12 are normally closed by a yielding bridging member 15. Clamping means comprising a bolt 16 threaded into the yoke member cooperates with a clamping member 17 to clamp the line wire 10 and the tap wire 18 in contact. Both wires are, of course, bare at the point of contact, although the tap wire also may be otherwise insulated, as by the insulator 19.

The end 13 of the yoke member 12 has near the upper end thereof, on the exterior surface, a groove or slot 20. This slot extends transversely of this end of the yoke member, and is adapted to receive an inwardly turned pivot portion 21 of the bridging member 15. A leaf spring or yielding member 22 is attached to the yoke member by any convenient means, as a screw 23, and engages the bridging member near that end which is adapted to be received by the slot 20. This mounting forms a yielding mounting for the bridging member 15, enabling it to pivot about the end 21 for movement in the plane of the yoke when pressure is applied to it from the top tending to push it downwardly.

The line wire 10 is enabled to easily enter the yoke member of the connector, since pressure of the wire 10 on the bridging member 15 causes the bridging member to yield and spring down-

wardly to the position shown in Fig. 5, thus permitting the wire to enter the yoke member past the bridging member. As soon as the wire 10 has been pushed sufficiently far into the yoke 5 member, to clear the end of the bridging member 15, however, the tension or pressure of the leaf spring 22 causes the bridging member to return to its normally closed position. The tap wire or other wire to be connected to the wire 10 may then be inserted into the yoke member parallel to the wire 10, and tightening of the bolt 16 will then act through the clamping member 17 to bring the two wires into the desired contacts.

The particular yoke member illustrated here- 15 with has an opening 24 through one side thereof, and an opening 25 through the other side thereof. The bridging member 15 is thus enabled to yield freely downwards, swinging in the space provided by these openings. At the upper end of 20 each of these openings, the ends of the yoke member 12 are provided with seats 26 and 27. These seats slope inwardly and downwardly, and are adapted to engage portions 28 and 29 of the bridging member, in order to prevent upward 25 movement of the bridging member when the wire 10 lies within the yoke member, and more particularly to take the strain imposed upon the bridging member by the upward thrust of the clamping means 16. The slope of these seats and 30 their relation to the bridging member 15 prevent any deformation of the yoke member when the clamping means 16 is pulled up tight, as by a wrench. The slope of the seats and the corresponding portions of the bridging member provides 35 an inward component under strain tending to hold the two ends of the yoke member from spreading apart.

While the connector illustrated in Figs. 1 to 5 is particularly designed to be stamped out of 40 sheet metal, it is to be understood that the connector may be made in other ways. The modified form illustrated in Figs. 6 and 7 is particularly designed for manufacture as a casting. The yoke member 30 is also provided with openings 31 and 45 32, and with seats 33 and 34 adapted to engage a bridging member 35. The bridging member is also provided with an inwardly turned end 36, adapted to cooperate with a slot 37 to provide a pivot for the yielding bridge member. A straight leaf spring 38 serves to hold the bridging member 50 in the desired position, since its shape does not require the correspondingly shaped leaf spring found in the previous modification. The clamping member 39 merely has a V-shaped upper portion adapted to engage the lower of the two wires 55 in the connector.

The clamping members 17 and 39, in cooperation with the bridging members 15 and 35, provide a fairly broad surface in contact with the wires, while the cooperation between the bridging 60 member and the seats provided for it at the top of the openings through the sides of the yoke member ensure correct distribution of the clamping strains, and thus considerable pressure may be exerted upon the wires without deforming either the wire or any part of the connector. This not only insures good electrical contact between the two wires, but also enables the connector to be removed and used again and again, 65 since there is no distortion of any part thereof.

The clamping member 17 is substantially U-shaped in cross-section, being designed to prevent spreading of stranded wires where the connector is used with wires of that type.

75 While I have shown and described certain em-

bodiments of my invention, it is to be understood that it is capable of many modifications. Changes, therefore, in the construction and arrangement may be made without departing from the spirit and scope of the invention as disclosed 5 in the appended claims, in which it is my intention to claim all novelty inherent in my invention as broadly as permissible, in view of the prior art.

What I regard as new, and desire to secure by Letters Patent, is:

1. A connector of the character described, including: a yoke member having openings through the sides thereof, said member being of sufficient size to receive two wires therein; a bridging member extending through said openings, said bridging member having one end thereof pivotally mounted on one end of said yoke member and the other end thereof adapted to swing downwardly to permit a line wire to enter said yoke past said bridging member; yielding means adapted to maintain said bridging member normally connecting the ends of said yoke; seats on said yoke member adapted to engage said bridging member to limit upward movement thereof, whereby said wire is prevented from leaving said yoke past said bridging member, said seats sloping inwardly and downwardly and being adapted to engage correspondingly sloped portions of said bridging member; a clamping member adapted to engage a second wire; and means for forcing said clamping member against said second wire to force said first mentioned wire against said bridging member, whereby said wires are clamped in contact.

2. A connector of the character described, comprising a U-shaped body having aligned apertures in the legs thereof adapted to receive a cross bar, a cross bar, means adjustably mounted in the base of said body to press conductors between said legs against said bar, said cross bar 40 being swingably mounted on one leg of said body to swing from a position where it extends through both said apertures to a position where it extends through only one aperture and the space between said legs is open to receive conductors, and cooperating means on said cross bar and one of said legs to prevent removal of the bar from said last named aperture.

3. A connector for electrical conductors comprising a U-shaped body having aligned apertures in the legs thereof, a cross bar movable transversely of said body to extend from one of said apertures into the other, said cross bar having end portions adapted to press inwardly on said legs to prevent the legs from spreading 55 apart, said cross bar having one end swingably mounted on one of the legs of said body so that it may be turned to move one of said end portions from the aperture in the corresponding leg and into the aperture in the other leg whereby 60 to provide for insertion of an unbroken conductor between the legs, said last named leg and said cross bar having cooperating members thereon preventing the cross bar from being detached from said last named leg, and means 65 adjustably mounted in the base of said body to press conductors between said legs against said cross bar said end portions of the cross bar and said legs having the engaging surfaces thereof sloped inwardly so that the pressure upon the 70 cross bar holds the legs from spreading apart.

4. A connector of the character described, comprising a U-shaped body having apertures in the legs thereof adapted to receive a cross bar, a cross bar, means adjustably mounted in 75

the base of said body to press conductors between said legs against said bar, said cross bar being movably mounted on one leg of said body to move from a position where it extends into both of said apertures to a position where it extends into only one aperture and the space between said legs is open to receive conductors, and spring

means pressing said cross bar into the first-named position, said spring means being yieldable under pressure upon said cross bar toward the base of said body to permit the cross bar to move to the second position. 5

WILLIAM J. BUEHRING.
